UNITED STATES PATENT OFFICE.

JULIUS J. MILLER, OF ST. JOSEPH, MICHIGAN, ASSIGNOR, BY MESNE ASSIGNMENTS,
TO WIREBOUNDS PATENTS COMPANY, OF KITTERY, MAINE, A CORPORATION OF
MAINE.

STAPLING-MACHINE.

1,291,072.

specification of Letters Patent. Patented Jan. 14, 1919.

Application filed December 14, 1908, Serial No. 467,360. Renewed May 18, 1917. Serial No. 169,494.

To all whom it may concern:

Be it known that I, JULIUS J. MILLER, a citizen of the United States of America, and resident of St. Joseph, Berrien county, Michigan, have invented a certain new and useful Improvement in Stapling-Machines, of which the following is a specification.

My invention relates to stapling machines of the type employed for fastening the heads or ends of wirebound boxes to cleats on the box sides, and which operate within the box for inserting the staples outwardly.

Among other objects, my invention is intended to provide an inside box stapler adapted for operating close to the inner sides and in the corners of the box and for forming its own staples near and directed toward the point of their application.

The invention further contemplates an arrangement whereby a standard, ordinary or other suitable staple former and driver may be employed for making the staples within the box; also the provision of a stapler adapted to reach within, support and gage the work and to form and drive the staples upwardly.

The nature of the invention will be best understood from the following description with reference to one form of machine containing an embodiment of my invention which is shown for illustration in the accompanying drawings.

In the said drawings:

Figure 1 is a side elevation of the illustrative machine, showing the frame thereof in vertical section.

Fig. 2 is a plan view of the said machine.

Fig. 3 is a vertical section on line 3—3 of Fig. 1.

Fig. 4 is an enlarged detail view of the staple driver with adjacent parts shown in section.

Fig. 5 is a perspective view of a wirebound box.

Fig. 6 is an enlarged side elevation of the staple supplying and driving devices, which in this case include a staple forming and driving mechanism arranged to insert the staple into a carrier or transfer device which positions it to be driven by a final or so-called secondary driver.

Fig. 7 is a section on line 7—7 of Fig. 6.

Fig. 8 is an enlarged plan view of the outer end portions of the rest or support

upon which the boxes are manipulated while the staples are being driven.

Fig. 9 is a top plan of the mechanism shown in Fig. 6 by which the staple is formed and inserted in the said carrier.

Fig. 10 is a section on line 10—10 in Fig. 6.

Fig. 11 is a perspective view of the carrier by which the staples are transferred to the position where they are driven in the box by the secondary driver.

Fig. 12 is an enlarged detail section on line 12—12 in Fig. 6.

Fig. 13 is a perspective of the staple-former.

Fig. 14 is a perspective of what may be termed the primary staple driver or ejector—that is to say, the elements associated with the former and which corresponds to an ordinary staple driver, but which in this case does not insert the staple directly into the box, being used merely for ejecting the staple and driving the same into the carrier and guide shown in Fig. 11.

The illustrative machine comprises a frame A having a horizontal arm B and a staple forming and driving mechanism carried thereby arranged for operation within the box, provided with devices for forming the staple with its points up and for driving the same upwardly at the terminal portion or nose of said arm; said terminal portion or nose which is formed by the converging plates b being adapted to reach into the box corners and to be engaged by the sides of the box to gage the position of the staples.

The character of work for which the machine is especially designed will be understood by reference to Fig. 5, which shows a wirebound box comprising sides 1 and 2 and bottom side 3, together with heads or end boards 4, and a swinging cover 5; the said sides, bottom and cover being provided with pre-attached cleats 6. Such a box is commonly formed by folding a wirebound box blank, composed of cleated sections, around the heads or end boards 4, the latter being ranged inside the cleats 6 and stapled thereto. The stapling of the heads to the cleats is preferably done by driving the staples from the interior of the box through the heads or end boards 4 and into the cleats, whereby the staples pass through the thin wood first and then enter the thicker pieces of wood constituting the cleats.

In performing such operation on the illustrative machine, the end board 4 rests upon the arm B, as seen in Fig. 6, and the operator manipulates the box on said arm while 5 operating the machine successively to drive a row of staples through each cleat,—that is to say, through the head or end board along lines which cause the staples to pass into the cleats; and in this operation the 10 tapered nose or terminal of the arm B serves as a guide for enabling the operator to position the work and to gage the staples from the box sides.

Referring to Fig. 1, the stapling mechanism as a whole comprises a forming mechanism G with associated wire-feeding and cutting devices (which mechanism may be a conventional staple former and driver), a staple guide and carrier C, and a final 15 driver I operating vertically at substantially the terminal of the arm B. To permit feeding and cutting a sufficient length of staple wire to form the required length of staple, while at the same time closely associating 20 the forming and driving devices to bring the entire operation substantially at the terminal of said arm, the staple forming and associated devices are arranged at an angle behind the driver I, so that the forming and 25 driving lines converge toward the point of application of the staple, and the staple is formed pointing toward the work and is shifted only slightly to position to be driven. The wire feeding, cutting, staple forming, 30 guiding and driving devices operate in substantially the same plane so as to avoid interference with the manipulation of the box on the supporting arm B, and with this arrangement of the mechanism the staples are 35 presented and driven crosswise of the box cleats.

The staple carrier and guide C consists of a tapered block provided with a vertical staple guide passage c in its forward end, 40 said block being pivoted to swing from the oblique position shown in Figs. 1 and 6 to a vertical position in which it fits between the converging plates b; in the latter position the guide passage c being directly over 45 the staple driver I. The back of the block C has pivot bearings c' at its top, and lower down pivot bearings c'' for connecting it with the operating rod D, which latter rocks the said block about its axis to move it back 50 and forth from one position to another. A retracting spring d is applied to the rod D and the rear end of the latter is provided with a roll or wheel d' adapted to engage a cam E on the drive shaft F. Said rod D 55 is mounted to slide endwise in bearings d'' on the frame, and the outer end of the rod preferably has a pin and slot connection with the block C, so that sufficient lost motion is provided to enable the horizontal re- 60 ciprocation of the rod to swing the block

about its axis. The said cam E is adapted to push the rod forward and bring the block C upwardly to a vertical position, so that the staple can be driven. The spring d then retracts the rod D at the proper time, causing 70 the said staple carrier and guide C to move back to a position for receiving another staple.

Staples are successively formed and introduced into the carrier block C by the 75 angularly arranged mechanism G, which may be of any suitable known or approved character. As shown, it comprises a known type of staple forming and driving mechanism, comprising a staple former g, staple 80 driver g¹, and loop bar or anvil g², which are operated in any known or suitable manner. The loop bar g² is pivoted at G¹. There is also the usual feed mechanism g³ for feeding the wire across the anvil or loop bar and 85 into position to be cut off and bent by the staple former. As usual, the driver g² is rigidly attached to an actuating head g⁴ which also carries the pawl or feed finger g⁵ for the staple wire feed mechanism, and 90 which head is operated by an arm g⁶ pivoted at g⁷ on the frame. As the mechanism is inverted, however, the spring g⁸ is applied for holding the staple former in operative position until after the driver g¹ has driven 95 the staple into the guide c of the block C. The operating arm g⁶ preferably has a lost motion connection with the head g⁴, in view of the fact that the driver and former must reciprocate in a straight line, whereas the 100 movement of the arm g⁶ is about an axis. The said arm g⁶ has its rear or shorter end portion provided with a roll or wheel g⁹ adapted to engage the cam H upon the shaft F, whereby the rotation of the shaft causes 105 the arm g⁶ to operate the said mechanism.

Referring further to the details of said mechanism G, the dog g¹⁰ is pivoted on the driver g¹ and engages the end of the former g, being held in this position by the spring 110 G¹¹ thereof. When the cam g¹² on said dog g¹⁰ strikes the cam g¹³ on the stationary head, after the staple is formed, the dog is then disengaged from the former g, permitting the driver g¹ to continue alone. When the 115 portion g¹⁴ of the driver g¹ engages the staple the latter is driven forward into the guide c of block C. This is possible, of course, by reason of the fact that the portion g¹⁵ of the loop bar moves into the groove g¹⁶ 120 on the driver g¹, thus allowing the loop bar to swing on its pivot and move out of the path of the portion g¹⁴ of the driver.

The driver g¹ of the mechanism above described may conveniently be termed the primary driver as distinguished from the one which drives the staple from the guide block C into the work, the latter driver being herein referred to as the secondary driver.

The said secondary driver I is provided and arranged to slide vertically in bearings i on the forward terminal of the frame. This driver is made thin and of a shape to 5 enter the guide passage c , when the block C is in its operative or vertical position, and thus the staple is driven upward by the said secondary driver. This driver I is operated by an arm i' fulcrumed at g^7 . It 10 will also be seen that the rear end of this arm is provided with a roll or wheel i^2 adapted to engage a cam J on the said drive shaft. Springs K and L are provided for holding the rear ends of the arms g^6 and i^2 15 in engagement with their respective cams.

A clamping arm or foot M is arranged above the arm or table B, and is fulcrumed at m , whereby its forward end m^1 may be brought downward to bear upon the head or 20 end board of the box, thereby resisting the upward thrust of the staple driver I during the operation of driving the staples. The rear end of this arm M is provided with a roll or wheel m^2 adapted to engage 25 a cam N on the drive shaft. A retracting spring n serves to keep the rear end of the arm M in engagement with its allotted operating cam on the shaft.

As before stated, the box head rests upon 30 the arm B during the stapling operation, and the tapered terminal or nose of the arm serves by engagement with the successive box sides for positioning the work and gaging the position of the staples. One side of the box 35 slides along against one of plates b until the staples at that side are driven, and then the bottom of the box slides straight across the flat outer face c^8 of the block c while another row of staples are driven, and then 40 the other side of the box slides outwardly upon the other plate b during the driving of the last row of staples. The foot or clamping arm M rises and releases the box after the driving of each staple, enabling 45 the operator to move the box the required distance for driving the next staple. The staples are made by the mechanism G, and are transferred from this mechanism by the block C to the position for driving, and the 50 driving is accomplished by the secondary driver I in the manner explained.

With the illustrative construction, the staple is formed and driven pointed toward the work, being formed substantially near the 55 driving point; in fact the staple is formed and thrust forward from the forming mechanism G to a position with its points nearest the place of insertion, so that the remaining movement for insertion of the staple into the work is comparatively slight. While there is some lateral shift in movement of the staple from forming to driving position, this is accomplished by an end-wise movement of the staple toward the 60 work; and thus in a sense the function of

the secondary driver is a continuation of that of the primary driver in driving the staple from the forming position to and in the work; and so the forming and driving are substantially one operation for practical purposes. Furthermore, by the angular disposition of the forming mechanism relative to the driver I, operating vertically beneath the forward end of the tapered nose of the arm B, the forming mechanism may 70 be of any necessary or desired width, according to the length of staple wire required to provide a staple of the desired length, while at the same time the entire mechanism is snugly arranged and closely associated 75 at the driving point, without interfering with the desirable capacity of the machine to drive the staples into the cleats close to the box sides and in the corners thereof.

Obviously the present invention is not 80 limited to any particular structural details or mode of operation, which may be variously modified; nor is it indispensable that all the features of the invention be used 85 conjointly since they may be used to advantage in various different combinations and sub-combinations.

What I claim as my invention is:

1. In a machine of the class described, the combination of a staple former, a primary 95 staple driver, a secondary staple driver, and means for receiving the staple so arranged that the same is caused to enter therein points first, and for then transferring the staple from the primary driver to the secondary driver, said means being stationary while receiving the staple, one driver being at an angle to the other, and both drivers arranged to extend toward the portion of the box to be stapled. 100

2. In a machine of the class described, the combination of a reciprocating staple former, means for feeding wire thereto, a pivoted loop bar or anvil for co-operating with the staple former in reducing the wire to the 110 desired form, a primary staple driver, working in the said staple former, a secondary staple driver, and a combined staple carrier and guide for receiving the staple so arranged that the same is caused to enter therein points first, and for then transferring the staple from the primary driver to the secondary driver, said means being stationary while receiving the staple, one driver being at an angle to the other, and both drivers arranged to extend toward the portion of the box to be stapled. 115

3. In a machine of the class described, means for making staples, a combined staple carrier and guide for receiving the staples 125 points first at one end thereof, arranged to remain stationary while the staples are being driven, means for moving said staple carrier and guide to driving position, thereby causing the staple to move along a line pass- 130

- ing through the point of insertion thereof in the box, and a driver arranged to enter the same end of said carrier and guide to drive the staples from the other end thereof.
- 5 4. In a machine of the class described, a staple forming and driving mechanism, a secondary staple driver disposed at an angle to the driver of said mechanism, each driver engaging the head of the staple, and pivoted means for transferring the staple from said mechanism to a position for the driving thereof by said secondary driver, said means causing the staple to move endwise toward the point of insertion.
- 10 5. In a machine of the class described, means for forming the staple, a pivoted guide for receiving the staple after it is formed, means for causing the staple to enter one end of the guide points first, while the guide is stationary, a device for entering the same end of said guide to drive the staple, and means for bringing said guide into alignment with said device, the arrangement being such that the staple enters the guide at one end and leaves at the other end thereof.
- 15 6. In a box stapling machine, a support for the head of the box, adapted to enter and engage the sides of the box to gage the position thereof, mechanism for making the staples with their points up, and means for driving the staples upward at the end of said support, said mechanism being disposed in position to form each staple with its points extending toward the cleat of the box, in a direction at an angle to the side of the box, and with the forming position of the staple close to the driving position thereof.
- 20 7. In a box stapling machine, a support for the head of the box, adapted to enter and engage the sides of the box to gage the position thereof, mechanism for making the staples with their points up, means for causing the staples to shift laterally to driving position, and means for driving the staples upward at the end of said support, said mechanism being disposed in position to form each staple with its points extending
- 25 toward the cleat of the box, in a direction at an angle to the side of the box, and with the forming position of the staple close to the driving position thereof.
- 30 8. An inside box end stapling machine comprising means for positioning the box, and a staple forming and driving mechanism for insertion in the box, constructed and arranged to form the staple, move the staple forward to driving position, and then insert the staple in the box, said mechanism disposed in position to form each staple with its points extending toward the cleat of the box, in a direction at an angle to the side of the box, and with the forming position
- 35 of the staple close to the driving position thereof.
9. A stapling machine having a staple guide, means for making and inserting a staple into one end of said guide, while the guide is stationary, means for shifting the guide to driving position, by movement thereof toward and against the material to be stapled, and means for entering the same end of the guide to drive the staple from the other end thereof.
- 40 10. An inside box end stapling machine provided with a support for the box end, and a staple forming and driving mechanism having a movable staple guide that serves as the end of said support, over and upon which the box rests in position for stapling, said guide receiving the staple with its points extending toward the cleat of the box.
- 45 11. An inside box end stapling machine comprising a staple forming mechanism inclined to extend lengthwise at an angle to the side of the box, to enable said mechanism to operate closer to the sides of the box; and to cause the forming position of the staple to approximate the driving position thereof, without necessitating larger cleats for the box, having means for transferring the staple into a different plane from the one in which it is formed, and means for driving the staple, all inside of the box.
- 50 12. An inside box end stapling machine provided with means for engaging the inside of the box to gage the position thereof, mechanism arranged for operation within the box to feed the wire crosswise of the direction of insertion of the staple, and by the same forward stroke that forms the staple, the said mechanism being arranged to feed the wire along a line extending through the planes of both the side and end of the box, and means arranged for operation within the box to drive the staple.
- 55 13. An inside box end stapling machine having a stapler head comprising a gage for properly positioning the head inside of the box, a reciprocating staple former and staple driver arranged in a manner to require lateral shift of the staple from forming to driving position, said former and driver being movable forward with the points of the staple toward the end of the box, means for feeding the wire across the path of the staple former, and means to form the staple by forward motion of the staple former toward the portion of the box to be stapled.
- 60 14. An inside box end stapling machine having a stapler head comprising a gage for properly positioning the head inside of the box, a reciprocating staple former and staple driver arranged in a manner to require lateral shift of the staple from forming to driving position, said former and driver being movable forward with the

- points of the staple toward the end of the box, means for feeding the wire across the path of the staple former, and means to form the staple by forward motion of the 5 staple former toward the portion of the box to be stapled, said staple former being disposed at an oblique angle to permit the forming position of the staple to approximate the driving position thereof, without necessitating larger cleats for the box. 10
15. An inside box end stapling machine having a stapler head comprising a gage for properly positioning the head inside of the box, a reciprocating staple former and staple driver arranged in a manner to require lateral shift of the staple from forming to driving position, said former and driver being movable forward with the points of the staple toward the end of the 20 box, means for feeding the wire across the path of the staple former, and means to form the staple by forward motion of the staple former toward the portion of the box to be stapled, a movable carrier and 25 guide, and means for transferring the staple from said staple former to said guide. 30
16. An inside box end stapling machine having a stapler head comprising a gage for properly positioning the head inside of the box, a reciprocating staple former and staple driver arranged in a manner to require lateral shift of the staple from forming to driving position, said former and driver being movable forward with the 35 points of the staple toward the end of the box, means for feeding the wire across the path of the staple former, means to form the staple by forward motion of the staple former toward the portion of the box to be 40 stapled, and a staple guide that receives the staples with the points thereof toward the end of the box. 45
17. An inside box end stapling machine having a stapler head comprising a gage for properly positioning the head inside of the box, a reciprocating staple former and staple driver arranged in a manner to require lateral shift of the staple from forming to driving position, said former and driver being 50 movable forward with the points of the staple toward the end of the box, and a movable staple guide that receives the staples with the points thereof toward the place of insertion in the box. 55
18. An inside box end stapling machine having a stapler head comprising a gage for properly positioning the head inside of the box, a reciprocating staple former and staple driver arranged in a manner to require lateral shift of the staple from forming to driving position, said former and driver being 60 movable forward with the points of the staple toward the end of the box, means for feeding the wire across the path of the staple former, means to form the staple by forward motion of the staple former toward the portion of the box to be 65 stapled, and a staple guide that receives the staples with the points thereof toward the end of the box. 70
19. An inside box end stapling machine having a stapler head comprising a gage for properly positioning the head inside of the box, a reciprocating staple former and staple driver arranged in a manner to require lateral shift of the staple from forming to driving position, said former and driver being 75 movable forward with the points of the staple toward the end of the box, means for feeding the wire across the path of the staple former, means to form the staple by forward motion of the staple former toward the position of the box to be 80 stapled, and a staple guide movable back and forth along a line passing through the 85 cleat. 90
20. An inside box end stapling machine having a stapler head comprising a gage for properly positioning the head inside of the box, a reciprocating staple former and staple driver arranged in a manner to require lateral shift of the staple from forming to driving position, said former and driver being movable forward with the 95 points of the staple toward the end of the box, means for feeding the wire across the path of the staple former, means to form the staple by forward motion of the staple former toward the portion of the box to be 100 stapled, and a staple guide and carrier beveled to fit the box and movable back and forth along a line passing through the 105 cleat. 110
21. An inside box end stapling machine having a staple head comprising a gage for properly positioning the head inside of the box, a reciprocating staple former and staple driver arranged in a manner to require lateral shift of the staple from forming to driving 115 position, said former and driver being movable forward with the points of the staple toward the end of the box, means for feeding the wire across the path of the staple former, means to form the staple by forward motion of the staple former toward the position of the box to be 120 stapled, and a staple guide movable along a line passing through the cleat, said line of movement being in the direction of the points of the staple and intersecting the point of insertion of the 125 staple. 130
22. An inside box end stapling machine comprising a staple forming and driving mechanism, and a gage for properly positioning the mechanism inside of the box, said mechanism comprising a staple guide having movement along a line passing 135

- through the end of the box at the desired point of insertion of the staple therein, said guide receiving the staple with the points thereof extending toward the portion of the 5 box to be stapled.
23. An inside box end stapling machine comprising a staple forming and driving mechanism, a gage for properly positioning the mechanism inside of the box, said mechanism comprising a staple guide having back and forth movement along a line passing through the end of the box at the desired point of insertion of the staple therein, and a staple driver that slides in said guide to 10 insert the staple in the direction in which said line enters said end wall, said guide receiving the staple with the points thereof extending toward the portion of the box to be stapled.
24. A machine for securing the heads of boxes in place by the insertion of staples outwardly from inside of the box, to fasten the heads to cleats previously secured to sides of the box, comprising a staple forming and driving mechanism arranged for 15 operation within the box, provided with devices for forming the staple with its points extending toward the cleat, and means for engaging the sides of the box to gage the 20 position of the staples.
25. A machine for securing the heads of boxes in place by the insertion of staples outwardly from inside of the box, to fasten the heads to cleats previously secured to 25 sides of the box, comprising a staple forming and driving mechanism arranged for operation within the box, provided with devices for forming the staple with its points extending toward the cleat, and means for 30 engaging the sides of the box to gage the position of the staples, said devices including a staple former disposed at an angle to the side of the box, and a loop bar cooperating with said former, pivoted to move 35 about an axis extending at an angle to both the head and side of the box.
26. A machine for securing the heads of boxes in place by the insertion of staples outwardly from inside of the box, to fasten the 40 heads to cleats previously secured to sides of the box, comprising a staple forming and driving mechanism arranged for operation within the box, provided with devices for forming the staple with its points extending 45 toward the cleat, and means for engaging the sides of the box to gage the position of the staples, said devices including a staple former disposed at an angle to the side of the box, and means to bend the staple by 50 forward movement of said former.
27. A machine for securing the heads of boxes in place by the insertion of staples outwardly from inside of the box, to fasten the 55 heads to cleats previously secured to sides of the box, comprising a staple forming and driving mechanism arranged for operation within the box, provided with devices for forming the staple with its points extending 60 toward the cleat, and means for engaging the sides of the box to gage the position of the staples, said devices including a staple former disposed at an angle to the side of the box, and means to bend the staple by 65 forward movement of said former.
28. A machine for securing the heads of boxes in place by the insertion of staples outwardly from inside of the box, to fasten the 70 heads to cleats previously secured to sides of the box, comprising a staple forming and driving mechanism arranged for operation within the box, provided with devices for forming the staple with its points extending 75 toward the cleat, and means for engaging the sides of the box to gage the position of the staples, said devices including a staple former, means to form the staple by forward movement of the former, said former being disposed at an angle to the side of the box, means for feeding the staple wire across the path of said former, and a staple driver associated with said former.
29. In a box-stapling machine, a support for the head of the box adapted to enter and engage the sides of the box to gage the position thereof, mechanism for making the staples with their points up, said mechanism being disposed in position to form each staple at an angle between the horizontal and the vertical, means to feed the finished 80 staple from the mechanism for making it laterally toward the point of its insertion in the box, and means for driving the staples upward at the end of said support.
30. In a box-stapling machine, a support 85 adapted to enter and gage the position of the box, mechanism for forming staples with their points up and at an angle between the horizontal and the vertical, means for receiving each staple at said angle from the forming mechanism, said receiving means being pivotably mounted and adapted to move through an arc to bring each staple into position to be driven, said staple-forming mechanism being inclined to reduce 90 the vertical dimension thereof and to reduce the distance of travel between the staple-forming and the staple-driving mechanism, whereby the mechanism is compact and capable of increased range of application.
31. A machine for securing box heads by inserting staples upwardly from within the box, to fasten heads to cleats pre-applied to the box sides, comprising an arm and a staple forming and driving mechanism carried thereby arranged for operation within the box, provided with devices for forming the staple with its points up and means for driving the same upwardly at the terminal portion of said arm, said terminal portion 125 130

adapted to reach into the box corners and to be engaged successively by the sides of the box to gage the position of the staple.

32. A machine for securing box heads by inserting staples upwardly from within the box, to fasten heads to cleats pre-applied to the box sides, comprising an arm having a terminal means for holding a staple and a mechanism carried by the arm arranged for 10 operation within the box provided with devices including a staple former for forming and supplying a staple to said holder with

its points up, and provided with means for driving the staple upward from said holder, said holder adapted to reach into the box 15 corners and to be engaged successively by the sides of the box for gaging the position of the staples.

Signed by me at St. Joseph, Mich. this 7th day of December, 1908.

JULIUS J. MILLER.
